GOLF BAG BOTTOM

John P. Murray, Jr., Princeton, N.J., assignor to Atlantic Products Corporation, Trenton, N.J., a corporation of New Jersey

Filed June 28, 1966, Ser. No. 2,844

Term of patent 14 years

(Cl. D34—5)

I claim:

The ornamental design for a golf bag bottom, as shown and described.
